UNITED STATES PATENT OFFICE.

JOHN J. BROWN, OF NEWARK, NEW JERSEY.

CONDENSING APPARATUS.

1,230,557.

Specification of Letters Patent. Patented June 19, 1917.

Application filed July 31, 1914. Serial No. 854,240.

To all whom it may concern:

Be it known that I, JOHN J. BROWN, a citizen of the United States, residing at Newark, in the county of Essex and State of New Jersey, have invented an Improvement 5 in Condensing Apparatus, of which the following is a specification.

This invention relates to an apparatus for condensing steam, and more particularly to 10 auxiliary devices employed in connection with the condenser proper, and the pump associated therewith, to produce a higher vacuum in the condenser proper, to materially increase the capacity of the pump, and also 15 to reclaim the heat of the steam employed in assisting the pump in withdrawing the non-condensable vapors from the condenser by utilizing the heat of this steam to raise the temperature of the condensate.

20 In carrying out my invention, I prefer to employ a main condenser, a combined hydraulic air and condensate pump, and vacuum intensifier or augmentor devices placed in the line or connections between the main 25 condenser and its pump.

The devices for intensifying or augmenting the vacuum preferably comprise a nozzle for the emission of a jet of steam for withdrawing or assisting in withdrawing the air 30 and non-condensable vapors from the main condenser, and connections whereby the condensate and the non-condensable vapors are separately withdrawn from the main condenser, and a combining chamber or auxiliary condenser, in which the condensate from 35 the condenser is utilized to condense the jet of steam from the said nozzle, this steam being thus additionally utilized to raise the temperature of the condensate.

40 I am aware that it is not broadly new to employ a jet of steam as a vacuum intensifier or augmentor, in a steam condensing system, but so far as the same has come to my knowledge, it is new to employ a jet of steam 45 in conjunction with a combining chamber or auxiliary condenser and a combined hydraulic air and condensate pump in such a manner that the rarefied non-condensable gases from the main condenser are compressed to 50 such an extent as to materially increase the efficiency of the pump, the capacity of the

pump being largely dependent upon the volume of the gas, and to also utilize the condensate from the main condenser, to condense the jet of steam, so that the temperature of the condensate is raised to a point 55 where it may be returned directly to the boilers, if necessary or desirable.

A condensing apparatus made in accordance with my present invention is illustrated 60 in the drawings forming part of this application, in which—

Figure 1 is a partial side elevation and longitudinal cross section of a condenser and pump, and the connections between the same. 65

Figs. 2, 3, and 4 are similar views illustrating, respectively, modified forms of my invention.

Referring to the drawing, and particularly to Fig. 1 in carrying out my invention, I 70 employ a condenser 10, which is illustrated as a surface condenser, and comprises a shell or casing 11, at the ends of which there are suitable tube plates 12, in and extending between which there are condenser tubes 13, 75 suitable water boxes 14 being connected at the respective ends of the shell, one of which, as is customary, is provided with an inlet and outlet for circulating water, one of these inlets being indicated at 15. The other circulating water connection is at the opposite side of the water box, and this, together with the inlet connection for the exhaust steam is not illustrated in this or either of the other figures of the drawing, this being unnecessary, inasmuch as these connections are well known requisites of surface condensers. 80

Associated with the condenser 10, I employ a pump 16, which is preferably a combined hydraulic air and condensate pump, 90 of the rotary type, in which the air and other non-condensable vapors, together with the condensate from the condenser, are admitted at a common suction and separately discharged. As illustrated in the drawing, the 95 suction of the pump 16 is indicated at 17, while the condensate discharge is indicated at 18, and the discharge for the air and non-condensable vapors is indicated at 19.

Extending between an outlet provided in 100 the shell of the condenser and the suction of the pump, is a pipe connection 20. The up-

per end of this is suitably attached to the shell of the condenser, and the lower end is connected to the suction of the pump by an elbow 21, or otherwise. Passing through the 5 port 22 of the shell of the condenser, and into the adjacent portion of the pipe 20, is an air and vapor discharge pipe 23. At its inner end, this is fitted with a cap or cover 24, and the air discharge connection 23 terminates at its outer end in a mouth 26, adjacent the contracted portion of the pipe connection 20, the air discharge pipe 23 being suitably secured in position and spaced apart from the upper portion of the pipe 20, so as to 10 leave an annular space 25 between the same.

The object of this construction is that the air and other non-condensable vapors may be withdrawn from the condenser shell through the pipe 23 entirely independently 15 of the condensate, which passes from the condenser shell, through the port 22, into the annular space 25, between the air discharge pipe 23 and the upper portion of the pipe connection 20.

25 The walls of the outer or lower portion 27 of the pipe connection 20 preferably diverge from its restricted central portion, so as to form a combining chamber, as hereinafter described.

30 I also employ a steam pipe 28, fitted with a valve 29, and leading from a suitable source of steam through the walls of the pipe connection 20 adjacent the condenser shell and also through the walls of the air 35 discharge pipe 23, within which the end of the steam pipe is fitted with a nozzle 30 directed toward the restricted end or mouth 26 of the air discharge pipe 23.

In the operation of this apparatus, and as 40 will be apparent, due to the fact that the air discharge pipe 23 is carried an appreciable distance into the shell of the condenser, the air and other non-condensable vapors are withdrawn from the condenser shell through 45 the pipe 23 independently of the condensate which passes through the port 22 into the annular space 25 between the air discharge pipe 23 and that portion of the pipe connection 20 adjacent the condenser shell.

50 The action of the combined air and condensate pump, in withdrawing the air and other non-condensable vapors from the condenser shell, is materially assisted, as will be understood, by the action of the steam 55 jet issuing from the nozzle 30, which acts as an ejector.

In view, also, of the restricted discharge orifice of the air discharge pipe 23, and due to the fact that as the steam and air and other vapors when withdrawn from the condenser and discharged from the pipe 23 are caused to commingle with the condensate at the discharge orifice of the pipe 23 and with-

in the combining chamber 27, the action of the steam jet also compresses the rarefied air 65 and gases as the same are withdrawn from the condenser shell, thereby materially increasing the efficiency of the pump, inasmuch as its capacity for handling the air and vapors is dependent upon the density of the 70 same, and furthermore as the condensate and the steam from the nozzle 30 are caused to commingle in the combining chamber 27, the condensate is utilized to condense the jet of steam from the nozzle 30, which, as will 75 be readily understood, raises its temperature, before the same reaches the pump, to such a point that, if necessary or desirable, the condensate may be returned directly to the boilers of the plant in which the condensing system is employed.

Referring to Fig. 2, it will be seen that I have illustrated a structure somewhat similar to that shown in Fig. 1 and described in connection therewith.

In this form of the invention, I prefer to employ an auxiliary condenser, indicated at 85 31. This is connected by a pipe 32 fitted with a valve 33 to an independent condensate discharge port 34 in the shell of the 90 condenser 10. The discharge of the auxiliary condenser is connected by an elbow 35, or otherwise, with the suction of the pump 13. In this form of the invention, I also employ a pipe 36, passing through a suitable 95 port therefor provided in the shell of the condenser, terminating at an appreciable distance within the condenser shell, and at its inner end fitted with a cap or cover 37.

Connected to the outer end of the pipe 36 100 is a valve 38, and connected to the valve 38 is another pipe section 39, the pipe 39 being connected to the auxiliary condenser 31 by the pipes 40 and 41, the former being connected to the outer end of the pipe 39 105 and the latter to the auxiliary condenser 31 at the inlet port 42 thereof. In this form of the invention, I also employ a steam pipe 43 fitted with a suitable valve 44, the pipe 43 passing through the wall of the pipe 40 and 110 having secured thereto within the said pipe 40 a suitable nozzle 45 for ejecting a jet of steam.

The operation of this apparatus is similar to that illustrated in Fig. 1, and described in 115 connection therewith, with the exception that the steam from the nozzle 45, with the air and other non-condensable vapors from the interior of the main condenser shell commingle with the condensate, and the steam 120 from the nozzle 45 is condensed thereby, in the auxiliary condenser 31, before the same reaches the combined air and condensate pump 16, the auxiliary condenser being provided with suitable baffle plates 46, 47 and 125 48, or other means, to insure the proper com-

mingling of these elements to condense the steam and permit the condensate to take up its heat before reaching the pump.

It is also to be noted that in this construction it will be necessary to leave considerable distance between the condenser shell and the adjacent end of the auxiliary condenser, in order to overcome any vacuum produced by the steam jet, and for this reason, as will be understood, this apparatus is not as efficient as the one shown and described in connection with Fig. 1.

Referring to Fig. 3, the construction of the modified form of the apparatus therein illustrated is similar in all respects to that shown in Fig. 2, and described in connection therewith, with the exception that I employ a separate or booster pump 49 for the condensate.

20 The suction of this booster pump 49 is connected by a pipe 50, in which there is a suitable valve 51 directly with the discharge port for the condensate in the shell of the condenser, while the discharge from the booster pump is connected by a pipe 52, which leads therefrom to the intake opening 53 in the side of the auxiliary condenser 31.

As will be readily appreciated, the object of employing the booster pump is to overcome any vacuum produced by the steam jet, and also to insure the condensate being delivered to the auxiliary condenser under all conditions.

Referring to Fig. 4, the modified form of the invention, therein illustrated, is also similar to that shown in Fig. 2, and described in connection therewith, with the exception that the suction of the pump 16 is directly connected to the port in the shell 40 of the condenser for the discharge of the condensate by a pipe 54, in which there is a suitable valve 55. The condensate discharge of the pump 16 is fitted with a pipe 56, in which there is a valve 57, and a pipe connection 58, in which there is a valve 59, extends between the discharge pipe 56 and the inlet port 60 in the side of the auxiliary condenser 31. As will be readily apparent, the pipe line 58, with the valves 57 and 59, 50 acts as a by-pass to govern and control the quantity of the condensate which is delivered to the auxiliary condenser, a part of the condensate being so delivered to condense the steam from the nozzle 45, and the other part of the condensate, not so utilized, passing directly by the pipe 56 to a hotwell, or elsewhere.

I claim as my invention—

1. The combination with a condenser and a combined hydraulic air and condensate pump, of means through which the condensate is withdrawn from the condenser, means through which the non-condensable vapors

are withdrawn from the condenser and entirely separately from the condensate, and 65 devices whereby and wherein the non-condensable vapors are all compressed and mixed with the entire volume of the condensate, so that the entire condensate and the compressed non-condensable vapors are 70 caused to mingle before they reach the pump.

2. The combination with a condenser and a combined hydraulic air and condensate pump, of a pipe leading from the condenser by which all the non condensable vapors are 75 continuously discharged, a steam jet nozzle within said pipe which at its outlet is contracted so as to cause the steam jet from said nozzle to compress the non condensable vapors, and a device in which the entire 80 volume of the condensate as same comes from the condenser is mingled with the steam and compressed non condensable vapors to condense the steam before the mixed condensate and compressed non condensable vapors reach the pump.

3. The combination with a condenser and a hydraulic air and condensate pump, of a pipe connection making communication between the interior of the condenser and the 90 suction of the pump, and which, adjacent its central portion, is of restricted cross section, a vapor discharge pipe extending an appreciable distance into the interior of the condenser and also into the adjacent portion 95 of the said pipe connection, and being concentric therewith, and a steam jet nozzle within the said vapor discharge pipe whereby the non-condensable vapors are drawn into and compressed in the said vapor discharge pipe, and the condensate through the annular space between the same and the adjacent portion of the pipe connection and the compressed non-condensable vapors and the steam from said nozzle are caused to 100 mingle with the condensate in the outer portion of the said pipe connection before reaching the said pump.

4. The combination with a surface condenser and a combined hydraulic air and 110 condensate pump, of a pipe connection, making communication between the interior of the condenser and the suction of the pump, and being of restricted cross section adjacent its central portion, a vapor discharge 115 pipe extending from a point an appreciable distance within the condenser to a point adjacent the restricted portion of the said pipe connection, that portion of the said vapor discharge pipe lying within the pipe 120 connection being concentric therewith and thereby providing an annular discharge passage for the condensate from the condenser terminating at the outer restricted end of the said vapor discharge pipe, and a steam jet 125 nozzle located within the said vapor dis-

charge pipe within the outer restricted end of which the non-condensable vapors are compressed by the steam from the said nozzle, the outer portion of said pipe connection comprises a combining chamber

steam is condensed before the same reach the said pump.

Signed by me this 25th day of July, 1914.
